[57] **CLAIM**

The ornamental design for a bottle, as shown and described.

DESCRIPTION

FIG. 1 is a top, front and left side perspective view of a bottle showing my new design;

FIG. 2 is a rear elevation thereof, the front elevation is a mirror image thereto;

FIG. 3 is a right side elevation thereof;

FIG. 4 is a left side elevation thereof;

FIG. 5 is top plan view thereof;

FIG. 6 is a bottom plan view thereof; and,

FIG. 7 is a perspective view of a second embodiment of the bottle that is the same as the first embodiment except that it is transparent.
